UNITED STATES PATENT OFFICE.

FRED W. McCORMICK, OF GRAND RAPIDS, MICHIGAN.

CUPBOARD LATCH.

Application filed October 18, 1926. Serial No. 142,256.

This invention relates to a cupboard latch and is primarily concerned with the economical production of a very simple, practical, durable and efficient latch which may be manufactured at very low cost and yet be of finished appearance and very satisfactory in operation. It is to these ends that my invention is directed.

For an understanding of the invention and the constructions embodying the same, reference may be had to the following description taken in connection with the accompanying drawing, in which,

Fig. 1 is an elevation showing the latch applied to a door, the keeper therefor being applied to the door casing or jam.

Fig. 2 is an enlarged transverse section through the latch.

Fig. 3 is an enlarged under plan view of the latch with the latch bolt in outer position.

Fig. 4 is a similar view showing the latch bolt retracted.

Fig. 5 is a perspective view of the outer casing of the latch, and

Fig. 6 is a perspective view of the latch bolt.

Like reference characters refer to like parts in the different figures of the drawing.

The latch is to be applied to a door, indicated at 1, near a vertical edge thereof and to engage with a keeper which is attached to the door casing or jam 2 near a vertical edge of the door jam.

In the construction of the latch an outer housing or casing of sheet metal is made which includes a central shallow trough or channel 3 from each side edge of which the metal is extended outwardly and curved downwardly as indicated at 4 and thence extends outwardly to make the ears 5 through which screws or similar fastenings are passed to attach the same to the door 1. The housing or casing at the edges of said ears is provided with a downturned rim 6 and it has ends 7 and 8 which join integrally with said rim. In one of the ends, that indicated at 7, an opening 9 is cut through which the latch bolt extends. The latch housing or casing is stamped from a single piece of sheet metal and is very cheap to make.

The latch bolt 10 is of metal somewhat wider than the width of the channel guide 3. On its upper side it is provided with a pro-

jection 11 of rectangular outline, the width of which is such that it may freely slide between the sides of the channel guide 3, while its height is substantially equal to the depth of said channel guide. The adjacent portions of the bolt 10 extending laterally under the part 4 of the housing, as shown in Fig. 2. The bolt at one end is formed with a beveled extension 12 which passes through the opening 9 in the end 7 of the latch housing.

The latch bolt is formed with an elongated slot 13 through it and at each side and at its inner end with lateral projections 14 which extend below the lower side of the bolt 10 making the extensions 15, as shown. The upper ends of the parts 14 are flat as indicated at 14^a and lie directly underneath the lateral portions 4 of the housing, one at each side of the channel guide 3 and prevent any tilting of the bolt about its longitudinal axis. At the inner end of the bolt an angular projection 16 is made back of the rear end of the slot 13 and this serves to limit the retraction of the bolt when it strikes against the end 8 of the housing or is in the position substantially like that shown in Fig. 4.

An operating member for the latch bolt is provided consisting of a stud 17 which passes through a suitable opening in the top of the housing or casing, and through the slot 13 in the bolt, being formed, directly above said housing, with an annular enlarged collar 18 which bears against the outer side of the channel guide 3. The stud 17 is thence extended farther outward, as indicated at 19 and terminates in a suitable knob 20 which may be grasped to be turned by hand. The inner end of the stud 17 has a sheet metal rocker arm 21 riveted thereto, the opposed projecting arms of which lie in front of the two feet 15 previously described. It is evident that on turning the stud 17 about its longitudinal axis by means of the knob 20, the rocker member 21 is rocked and, irrespective of which direction the stud is turned, the bolt will be moved from the position shown in Fig. 3 to or toward that shown in Fig. 4. A coiled spring 22 is disposed in the slot 13 between the outer end of said slot and the relatively fixed stud 17. The inward movement of the bolt on its retraction compresses the spring so that on release of the knob 20 the spring moves the bolt outward or to the po-

sition shown in Fig. 3, it being stopped when the connecting portion 16 at the rear end of the slot 13 comes against the stud 17.

When the latch is secured to the door 1 as shown in Fig. 1 the projecting end 12 of the latch bolt extends across the meeting edges of the door and the door jam 2. A keeper 24 has ears 25 through which screws pass to fasten the keeper on the door and it is located so that the beveled end of the latch bolt extension 12 will ride against a side of the keeper retracting the bolt automatically until it comes to an opening in the side of the keeper in to which it will pass. The keeper being of old and well known construction will not be further specifically described.

This latch is of simple construction but is very satisfactory in operation. The channel guide 3 in which the projecting portion 11 of the latch bolt rides serves to guide the bolt in its reciprocations and holds it from any tendency to swing laterally in either direction from a straight reciprocatory movement, irrespective of the application of the force which moves the bolt to one of the feet 15 at a point considerably to one side of the longitudinal axis of the bolt. The rear projection 16 on the bolt makes a very effective stop to limit the movement of the bolt so that the outer extension 12 thereof is never moved back so far that it will pass within the housing or casing. Moreover the closing of the rear end of the bolt back of the slot 13 adds to the strength and durability and rigidity of the bolt. The construction has proved very practical. The invention is de-

fined in the appended claims and is to be considered comprehensive of all forms of structure coming within their scope.

I claim:

1. In a latch, a housing of sheet metal formed in its outer side with an elongated guide, a latch bolt slidably received in said guide to hold the bolt against lateral movement, adjacent portions of the bolt near said projections extending under adjacent portions of the housing near the guide and thereby holding the bolt against tilting about its longitudinal axis, manually operable means for retracting the bolt, and spring means for normally projecting the bolt outwardly at one side of the housing.

2. In a latch, a housing of sheet metal formed in its outer side with an elongated channel shaped guide and having an open inner side, a latch bolt narrower than said housing located within said housing and having an extension to enter said guide, said latch bolt having an elongated opening therethrough and also having a lug at each side thereof, an operating member pivotally mounted in the housing and extending through the elongated opening in the latch bolt and an arm fixed to the inner end of the operating member in a position to retain the latch bolt within the housing, the opposite ends of said arm being adapted to respectively engage the lugs on the latch bolt for actuating the same.

In testimony whereof I affix my signature.

FRED W. McCORMICK.
